New York, N. Y., a corporation of Delaware

Application September 1, 1945, Serial No. 613,979

9 Claims. (Cl. 250—36)

1

This invention relates to the generation of polyphase electric power, and more in particular to a polyphase oscillation generating system wherein the frequency of oscillation may be varied as desired.

An object of this invention is to provide a polyphase oscillator whose frequency may be varied as desired in a dependable and efficient manner. A further object is to provide such a system which is adaptable for use, for example, in a frequency modulation system where the center frequency may be controlled for monitoring purposes. A further object is to provide a system of the above character which is simple and practical in construction and which is dependable and adaptable for use where it is important to provide a desired preciseness of response to the control influence. These and other objects will be in part obvious and in part pointed out below.

The invention accordingly consists in the features of construction, combinations of elements, arrangements of parts and in the several steps and relation and order of each of the same to one or more of the others, all as will be illustratively described herein, and the scope of the application of which will be indicated in the following claims.

In the drawings:

Figure 1 is a simplified circuit diagram showing one embodiment of the invention; and

Figure 2 is similar to Figure 1, but shows another embodiment of the invention.

Under certain circumstances, it is desirable to provide a polyphase oscillator whose frequency may be varied precisely as desired in response to some control effect. For example, polyphase oscillation may be utilized advantageously in certain frequency-modulated radio equipment. In such a polyphase oscillating system it is desirable to provide for the precise variation of the frequency of oscillation and to provide an arrangement whereby this frequency may be changed rapidly in response to the varying control influence. In accordance with the present invention, a polyphase source of electric power is provided wherein the frequency is varied by electronic means to permit such a rapid response. Illustratively, a three-phase system is shown in which inherently the phase angle between the phases is maintained constant and the frequency is varied by the simple procedure of changing a control potential applied to a plurality of electronic devices. This is achieved by changing the impedance of certain elements of a group of phase-shift circuits whereby the frequency of oscillation

of the system changes in order to maintain the constant phase angle between phases which is inherent in this circuit.

Referring particularly to Figure 1 of the drawings, a three-phase circuit is shown in simplified form wherein the filament and plate supply circuits for the various tubes are omitted, and wherein a three-phase radio-frequency power output is supplied at A, B, and C. This circuit includes three three-element oscillator vacuum tubes 1, 2 and 3, having cathodes 4, 5 and 6, respectively, grids 7, 8 and 9 and plates 10, 11 and 12, respectively. The plates of these tubes are connected to the output leads at A, B and C through coupling condensers 13, 14 and 15. The output voltage of tube 1 is fed from its plate 10 through an interstage coupling condenser 16 to grid 8 of tube 2. Similarly, the output voltages of tubes 2 and 3 are fed from their plates respectively to the grids 9 and 7 of tubes 3 and 1 through interstage coupling condensers 17 and 18. The plates of tubes 1, 2 and 3 are connected to a suitable source of high potential direct current through resistors 19, 20 and 21, respectively, and the cathodes of these tubes are connected to ground through resistors 22, 23 and 24, respectively.

Grid 8 of tube 2 is connected to ground through a pair of series-connected resistors 25 and 26; similarly, grid 9 is connected to ground through series-connected resistors 27 and 28, and grid 7 is connected to ground through series-connected resistors 29 and 30. The juncture 31 between resistors 25 and 26 is connected through a condenser 32 to the juncture 33 of a resistor 34 and the plate 35 of a three-element control vacuum tube 36. Control tube 36 has a control grid 37 and a cathode 38 which is connected to ground. In a similar manner, the juncture 39 between resistors 27 and 28 is connected through a condenser 40 to the juncture 41 between a resistor 42 and the plate 43 of a control vacuum tube 44 which has a grid 45 and a grounded cathode 46; and, the juncture 47 between resistors 29 and 30 is connected through a condenser 48 to the juncture 49 between a resistor 50 and the plate 51 of a control vacuum tube 52 which has a grid 53 and a grounded cathode 54. Resistors 34, 42 and 50 are connected to the positive side of a suitable source of high potential direct current, the negative side of which is connected to cathodes 38, 46 and 54 through ground. Grids 37, 45 and 53 of the control tubes 36, 44 and 52 are connected together and to one terminal 55 of a suitable control potential E_m , the other ter-

minal 56 of which is connected to ground and thence to cathodes 38, 46 and 54.

In this circuit each of the oscillator tubes 1, 2 and 3 is connected to provide one of the three phases of the polyphase output and each tube exerts a control influence upon the tube of the next phase so that the three phases are held in their exact 120° relationship. The control effect by each tube upon the tube of the next phase is exerted through an interstage phase shift circuit, there being three such circuits which are identical in components, characteristics and operation. The phase shift circuit by which tube 1 controls tube 2 is formed by capacitance and resistance connected in series, the capacitance being supplied by a condenser 16 and there being a series resistance circuit to ground formed in part by resistors 25 and 26. The remainder of the resistance circuit is formed by two additional connections to ground which are from juncture 31 through condenser 32, which has low impedance at the high frequency of operation, and thence, through control tube 36 to ground, and through resistor 34 and a connection to ground (not shown) which has low impedance at the high frequency of operation. Thus, it may be considered that grid 8 is connected to ground through resistor 25 to juncture 31 and thence through a network circuit having three parallel branches formed, respectively, by resistor 26, control tube 36 and resistor 34. This is because condenser 32 and the impedance connecting the positive side of resistor 34 to ground may be ignored at the high frequency of operation.

For purposes of explanation, we will assume that grid 37 of control tube 36 has a normal grid bias and therefore control tube 36 may be considered as an equivalent fixed resistor, the value of which is equal to the internal impedance of the tube, so that in fact resistors 25, 26 and 34 and control tube 36 may be considered as being a single resistor which connects grid 8 to ground and which forms the resistance component of the phase shift circuit. The value of this single resistance component is such with respect to condenser 16 that at the normal frequency of operation there is a 60° phase shift on grid 8 with respect to plate 10. This 60° phase shift between plate 10 and grid 8 combines with the 180° phase shift produced in the vacuum tube 2 between grid 8 and plate 11 to produce the net phase shift desired between the two tubes. That is, it will be considered that the 60° phase shift is subtractive with respect to the 180° phase shift of the tube, and thus there is a net phase shift of 120°, but if the 60° phase shift is considered as additive with respect to the 180° phase shift of the tube, the net phase shift is 240°; and with either the additive or subtractive relationship the desired net effect is obtained.

In a similar manner, oscillator tube 2 controls oscillator tube 3, and oscillator tube 3 controls oscillator tube 1. Thus, plate 11 of tube 2 is connected to grid 9 of tube 3 through an interstage phase shift circuit formed by condenser 17, resistors 27, 28 and 42 and control tube 44; and, plate 12 of oscillator tube 3 is connected to grid 7 of oscillator tube 1 through an interstage phase shift circuit formed by condenser 18, resistors 29, 30 and 50 and control tube 52. Each of these two phase shift circuits operates the same as the circuit connecting plate 10 and grid 8, and, during operation, each phase main-

tains the next phase in its proper relationship, and any tendency for one phase to deviate from this relationship is automatically corrected.

Control tubes 36, 44 and 52 have been considered as having a normal grid bias on their grids so that they act as fixed resistors. However, when there is a control signal at E_m , the grid bias of each of these grids is changed with the result that the internal impedance or equivalent resistance of each of the control tubes is changed. Thus, for example, a change in the grid bias of grid 37 changes the equivalent resistance of control tube 36 and thus changes the effective resistance connecting grid 8 of oscillator tube 2 to ground. This tends to cause a change in the phase shift produced by this phase shift circuit because the phase shift depends upon the relative values of the capacitance of condenser 16 and the effective resistance connecting grid 8 to ground. However, as indicated above, the three oscillator tubes 1, 2 and 3 control each other, and, therefore, the phase shift relationship between phases does not change, but rather the frequency of oscillation changes in such a manner as to maintain the desired fixed phase shift relationship between phases. In this way the simple action of changing the grid bias of control tubes 36, 46 and 52 changes the frequency of oscillation of the oscillator system. For example, if the control signal E_m increases, the impedances of tubes 36, 46 and 52 decrease; then a higher frequency is necessary in order to maintain the 60° phase shift at the oscillator tube grids and the circuit therefore oscillates at this higher frequency. Conversely, a reduction in the control signal E_m causes a reduction in the oscillating frequency. The components of the circuit are such as to permit operation within the frequency range desired so that a dependable source of polyphase oscillation is provided. When desired more than three phases may be provided by adding additional oscillator tubes and interstage phase shift coupling circuits, it being understood that due consideration must be given to obtaining the proper fixed phase shift between phases.

In the embodiment of Figure 2 a polyphase oscillator system such as that of Figure 1 is provided wherein the frequency of oscillation is controlled in accordance with a control signal E_m , and in addition another control influence may be provided where the frequency of modulation may be additionally regulated. This second control influence may be for monitoring purposes so that the normal frequency of oscillation is regulated by a direct current voltage and then the control signal E_m exerts a frequency modulating effect to make the system oscillate at frequencies above and below the normal frequency.

In addition to this monitoring control, the embodiment of Figure 2 is provided with means to control automatically the amplitude of oscillation. The amplitude of oscillation is controlled by a set of diode rectifiers in the oscillator tubes. This amplitude control system will now be discussed. Oscillator tubes 57, 58 and 59 correspond to tubes 1, 2 and 3, respectively, and in addition to the elements of tubes 1, 2 and 3 (which are correspondingly numbered), tubes 57, 58 and 59 are provided with screen grids 60, 61 and 62 which are connected to their respective cathodes, amplitude control grids 63, 64 and 65 and rectifier anodes 66, 67 and 68. Grid 63 of tube 57 is connected to the juncture 69 of a condenser 70 and a resistor 71; the other side of resistor 71

is connected to the positive side of a source of direct current potential, the negative side of which is connected to condenser 10 through ground. Juncture 69 is also connected to the positive side of a battery 72, the negative side of which is connected to anode 67. Similarly, grid 64 of tube 58 is connected at the juncture 73 to one side of a grounded condenser 74, a resistor 75 and through a battery 76 to anode 58; and, grid 65 of tube 59 is connected at the juncture 77 to a grounded condenser 78, a resistor 79 and through a battery 80 to anode 66. Resistors 75 and 79 are also connected to the positive side of a source of direct current to which resistor 71 is connected.

As indicated above, the circuit of Figure 2 oscillates in the same general manner as does the circuit of Figure 1, and, initially, grids 63, 64 and 65 are maintained positive so that they do not interfere with the polyphase oscillation. However, if excessive amplitude of oscillation should tend to occur in one of the oscillator tubes, such as in tube 58, the potential of cathode 5 will fall below that of anode 67. This will cause current to flow through the diode formed by cathode 5 and anode 67 so as to lower the potential of grid 63 to such an extent that the amplification of tube 57 is decreased. There is a similar action in each of the other two amplitude control circuits; that is, the diode formed by cathode 6 and anode 68 limits the amplitude of oscillation in tube 58, and the diode formed by cathode 4 and anode 66 of tube 57 controls the amplitude of oscillation in tube 59. Under some circumstances it is desirable to replace batteries 72, 76 and 80 with resistors shunted to ground by a condenser.

The monitoring control referred to above is provided by effecting a change in the basic effective resistances of the three interstage phase shift circuits. Accordingly, resistors 34, 42 and 50 are replaced by three monitor control vacuum tubes 81, 82 and 83. These tubes have, respectively, plates 84, 85 and 86, grids 87, 88 and 89 and cathodes 90, 91 and 92. The plates of these monitor control tubes are connected to the positive side of the direct current source, as were the corresponding resistors in Figure 1, and thence to ground through the direct current sources 107 shunted with capacitors 108 which have low impedance at the high frequency of operation, and cathodes 90, 91 and 92 are connected, respectively, to junctures 33, 41 and 49. Grids 87, 88 and 89 are connected together and to the plate 93 of a vacuum tube 94 which has a cathode 95, a control grid 96 and grids 97 and 98.

Plate 93 is connected to the juncture 99 between a pair of voltage divider resistors 100 and 101, which are connected in series and form a voltage divider between the positive terminal and the grounded negative terminal of a source of direct current. Grid 98 is connected to the juncture 102 of a condenser 103 (the other side of which is grounded) and a resistor 104 which has its other side connected to the positive side of a source of direct current, the negative side of which is grounded. Control grid 96 is connected to one terminal 105 of a monitor control potential E_c , the other terminal 106 of which is connected to the grounded cathode 95. Illustratively, potential E_c is a direct current potential, and its value controls the current flow through tube 94. This current flow determines the potential of juncture 99 of the voltage divider and, therefore, the grid bias of the grids 87, 88 and 89 of tubes 75

81, 82 and 83. Thus, the internal impedance of tubes 81, 82 and 83 is readily controlled.

As many possible embodiments may be made of the mechanical features of the above invention and as the art herein described might be varied in various parts, all without departing from the scope of the invention, it is to be understood that all matter hereinabove set forth, or shown in the accompanying drawings, is to be interpreted as illustrative and not in a limiting sense.

I claim:

1. A polyphase oscillation generating system comprising a plurality of amplifier stages, a plurality of non-resonant phase shifting networks cyclically interconnecting said stages and composed of reactive and resistive impedance means, the resistive impedance means of each of said networks including a pair of electronic discharge devices connected in tandem, a source of space current connected across said tandem-connected devices, means for varying the internal impedance of one of said electronic discharge devices of each pair, and different means for varying the internal impedance of the other of said electronic discharge devices of each pair, whereby the operating frequency of the system may be altered.

2. A system as claimed in claim 1 wherein each of said amplifier stages is represented by a vacuum tube having a cathode, a plate and a plurality of grids, further comprising means for limiting the amplitude of oscillations generated by the system, said last means including a diode anode placed in each of said tubes adjacent the cathode thereof, an impedance connected to each cathode whereby the cathode potential will vary with the current through the tube, means for biasing said diode anode to a potential more negative than that of the associated cathode except upon occurrence of amplitudes above a predetermined limit, a condenser shunting said diode anode, said cathode and said impedance, and means connecting said diode anode to one of the grids of one of said tubes.

3. A system as claimed in claim 2, wherein the diode anode of each stage is connected to a grid of the preceding stage.

4. A system as claimed in claim 3, wherein each stage comprises a pentode tube and wherein the diode anode of each stage is connected to the screen grid of the preceding stage.

5. A polyphase oscillation generating system comprising a plurality of amplifier stages, a plurality of non-resonant phase shifting networks cyclically interconnecting said stages and composed of capacitive and resistive impedance means, the resistive impedance means of each of said networks including a pair of triodes, means connecting the plate of one triode of each pair to the cathode of the other triode, a condenser forming part of said capacitive impedance means connected to said plate and said cathode, a source of space current connected across said two triodes in series, means for grounding the cathode of said one triode at least for the frequencies in the operating range of the system, means for applying a signal potential to the grid of said one triode whereby the operating frequency of the system may be modulated, and means for applying a control potential to the grid of said other triode whereby the mean operating frequency of the system may be varied.

6. A system as claimed in claim 5, wherein the plate of said other triode is grounded for the frequencies in the operating range of the system.

7. A system as claimed in claim 6, wherein the

means for applying said control potential comprise a voltage divider, a connection between an intermediate point of said voltage divider and the grid of said other triode, an electronic discharge device shunting part of said voltage divider, and means for varying the conductivity of said electronic discharge device.

8. A system as claimed in claim 7, wherein said electronic discharge device is a pentode.

9. A system as claimed in claim 5 wherein each of said amplifier stages is represented by a vacuum tube having a cathode, a control grid, a screen grid and a plate, the plate of each stage being coupled to the control grid of a succeeding stage over a respective one of said phase shifting networks, further comprising means for limiting the amplitude of oscillations generated by the system, said last means including a diode anode placed in each of said tubes adjacent the cathode thereof, a resistor connected between each cathode and ground, means for biasing said diode anode to a potential more negative than that of the associated cathode except upon occurrence of amplitudes above a predetermined limit, a condenser shunting said diode anode, cathode and cathode resistor, and means connecting the diode

5 anode of each stage to the screen grid of the preceding stage.
